UNITED STATES PATENT OFFICE

PAUL H. SCHULZ, OF MOLINE, ILLINOIS

RECORD CHANGING MECHANISM

Application filed May 31, 1929. Serial No. 367,348.

My invention has reference to a record changing mechanism of that kind by the operation of which a number of talking machine records can be fed in succession from a common storage place to the apparatus of a sound reproducing machine, and, after being played, removed from said apparatus and reassembled for return to the place of storage, all of the operations connected therewith being automatically performed.

One of the purposes of the invention is to greatly increase the capacity of the machine, so that more than double the number of records can be played consecutively than is now possible with machines of that type, making it a desirable machine for use in restaurants, dance halls, and the like, where it is desired to have the machine run for a considerable length of time without attention. At the same time the device is of comparatively simple construction, and can be produced at so low a cost as to warrant the same being used to a large extent in the homes.

Another purpose of the invention is the provision of novel and effective mechanism for conveying the records in regular order to the reproducing devices, and removing the same therefrom, a very brief time being required for removing one record from the turntable of the machine and positioning another one thereon.

The invention is shown and set forth herein in its special adaptation for use with a radio outfit, whereby the sounds that are reproduced by the machine are amplified by the loud speaker of the radio apparatus.

The invention embraces several groups of mechanisms, each independent in a way, but inter-related and cooperating with each other to bring about the desired results. The function of the first of these groups is to support a plurality of records in position for successive release and delivery to the conveying mechanism. The second group includes the apparatus for receiving the records, one at a

time, from the storage mechanism and conveying it to the reproducing apparatus, and later conducting the record from the reproducing apparatus to the record assembling device. This latter device comprises another and third group of parts, of a novel character. Still another group takes in the reproducing mechanism, including the tone arm and pick-up thereof. Associated with these various groups are frame structures for the support thereof, and drive mechanisms by means of which they are operated.

The construction, arrangement, and operation of the various parts of the invention will be more fully understood from the following specification, taken in connection with the accompanying drawings, in which is portrayed one embodiment of the machine, and in which,—

Fig. 1 is a side elevation of the machine, with some of the frame broken away.

Fig. 2 is a plan view thereof, with part of the superstructure removed.

Fig. 3 is a side elevation of that side of the machine opposite to the side shown in Fig. 1.

Fig. 4 is a diagram of the electric system used in connection with the invention.

Group A includes a base 1 and frame 2, which parts are also common to other portions of the machine. The side-pieces of the frame are united by a cross-plate 3, secured to which is a loop 4, in which is fixed the lower end of a rod 5, inclined upwardly at an angle of approximately forty-five degrees, and passing through a cross-plate 6, on the upper ends of brackets 7, also forming a part of the frame. Slidable on the rod 5 is a tube 8, provided at its lower end with an arm 9, with which is connected one end of a coiled spring 10, the other end of which is attached to the cross-plate 6. Fixed to the upper end of the tube 8 is a disk 11, adapted for the support of a plurality of records 40, with the projecting end of the rod 5 passing

through the central openings in the records, and retaining them in position on the disk. It will be evident that the disk 11 and records thereon are held in an inclined position at right angles with the axis of the rod 5, and that if permitted to do so said records would move downwardly of their own weight.

The tendency of the spring 10 is to move the disk 11 and pile of records upwardly, but this is normally prevented by means of a brake-lever 12, fulcrumed on the frame at *a*, and connected by a coiled spring 13 with a pin 14 in the lower part of the frame. The tendency of said spring is to hold the end of the lever 12 in engagement with the tube 8, holding the same from movement. Projected upwardly from one side of the frame is a plate 15, from which projects laterally a tubular support 16, in which is a rock-shaft 17. On the inner end of the shaft 17 is an arm 18, normally in line with the rod 5, and provided on its lower end with a stop 19, against which the upper record 40 is in contact. The space between the stop 19 and end of the rod 5 is slightly wider than the thickness of a record, permitting one record at a time to be removed from the pile on the disk 11. Projecting downwardly from the stop 19 is a pin 20, which enters the opening in the topmost record, and holds the same from accidental release. By means of mechanism hereinafter set forth the arm 18 can be swung toward the center of the machine when it is desired to eject the record from the pile. The initial movement of the record is caused by the pin 20, the end of which is spaced from the upper end of the rod 5, to permit of the free movement of the pin. In the continued movement of the arm 18 the stop 19 moves away from the record and the pin 20 disengages therefrom, whereupon the record continues its downward movement by force of gravity, and is received by 45 the conveying mechanism hereinafter described.

Journalized in the frame 2 is a main drive-shaft 22, on which is fixed a worm gear wheel 23, in mesh with a worm drive 24 on the shaft 25 of a motor 26, supported on the base 1. On the outer end of the shaft 22 is a crank-arm 27, the crank-pin 28 of which is engaged in a slot 29 in the lower end of a connecting rod 30, the upper end of which has a pivotal connection with an arm 31, fixed to the outer end of the rock-shaft 17. A coiled spring 32 is connected at one end to the connecting rod 30, and at the other end to the support 15, the tendency of said spring being to give an upward urge to the connecting rod at all times.

At one point in the cycle of operations it is desired to have the brake-lever 12 released momentarily, during which interval the disk 65 11 and records thereon are moved upwardly

a distance corresponding with the thickness of a single record. For this purpose an angle-lever 36 is pivoted to the frame, as at *b*, the short arm of said lever bearing against the long arm of the lever 12. The plate 36 is bent outwardly at its free end into an arm 37, which is again bent to form a trip 38, which is in the line of movement of the outer end of the crank-arm 27. As the crank-arm passes beneath the trip it raises it, tipping the plate 36 upwardly and raising the long end of the brake lever 12. This permits the tube 8 and disk 11 with its load to move upwardly under the force of the spring 10, and as this action is timed to immediately follow the discharge of a record from the top of the pile, such records is replaced in position by the one next below the same. In some cases, as when loading the disk 11 with a supply of records, it is necessary to release the brake, and this can be accomplished by means of a hand-lever 39, pivoted to the frame as at *c*, the lower end of said hand-lever engaging the long end of the brake-lever and forcing the same upwardly, releasing the tube 8, and permitting the disk 11 to be forced downwardly to its lowest point.

During the feeding interval for the records, when the brake 12 is released, the crank-arm 27 is at the upper end of its movement, with the connecting rod 30 in a substantially vertical position, as shown in broken lines at X in Fig. 3, with the crank-pin 28 at the upper end of the slot 29. In this position the arm 18 is in its normal position, in line with the rod 5, and it is practically locked in such position during the release of the brake 12, preventing accidental discharge of the records from the rod. When the disk is being supplied with records it is desired to have the arm 18 out of the way, and with the crank-arm 27 in a certain other position the slot 29 permits the rod 30 to be thrown forwardly, as shown in broken lines at Y, with the arm 18 turned well out of the way. This can be accomplished at a time when the storage devices are at rest, as will be hereinafter mentioned.

Group B, which takes in the mechanism for receiving and handling the records after they leave the storage group, is pictured more specially in Figs. 1 and 2, and there is necessarily included therein a part of the reproducing apparatus, such as a motor 41 for driving the same, located beneath the base 1, and provided with a vertical shaft 42, to which is fixed a turn-table 43. The upper end of said shaft is formed into a pin 44, to receive the record, and assist in centering it on the turn-table. The receiving apparatus embraces a pair of supports 45 on the end of the frame 2, in the upper ends of which is rockingly supported a rod 46, to which is fixed a pair of bearings 47, supporting a plate 48, from the opposite ends of which is pro-

jected a pair of arms 49, having side flanges or guides 50. Upon said arms being raised into inclined position, as shown in broken lines in Fig. 1, the released record slides down said arms and is stopped by a pair of bumpers 51 supported by the plate 48. These bumpers also serve as gauges for properly positioning the record with reference to the turn-table 43.

10 The means for moving the plate 48 and arms 49 consists of an arm 52 fixed to the rod 46 and connected by a plate or rod 53 with the end of an arm 54, pivoted to the frame 2 at d. The arm 54 is provided with a roller 55 for engagement by a cam 56 on the shaft 22. The rotation of said cam serves to move the arm 54 forwardly, as shown in broken lines, the arm 52 being moved in the same direction, causing the arms 49 to swing upwardly. 15 The conformation of the cam is such that the receiving device at first is carried into the position shown in broken lines at Z, in Fig. 1, this movement enabling said device to deliver the record which has just been played to the re-assembling mechanism. The arms 49 are then moved downwardly again into the inclined position before referred to, in which the record is delivered thereto. The ends of the arms are curved 20 upwardly, and as the record slides over the curved portions it tends to raise the forward edge of the record a little, and prevent it from scratching the record just beneath it. After receiving the record the arms move 25 downwardly again, passing on opposite sides of the turn-table and to a point slightly below the same, depositing the record on such turn-table. The connections for the plate 48 are angularly disposed, and in the final 30 movement thereof downwardly the gauges 51 draw away from the edge of the record, so as not to interfere with the rotation thereof. A coiled spring 57 connects the arm 54 with the frame, and holds said arm in operative 35 position at all times with reference to the cam 56.

Group C, which includes the mechanism for reassembling the records, consists of an inclined support 59, in the upper end of which is a bearing 60, to receive a rod 61, which is held in place by a set-screw 62 in the bearing. A washer 63 of elastic material serves as a buffer for the records, which are strung on the rod 61, one at a time. The 40 receiving end of the rod is curved, as shown, the curve therein serving to raise the records a little, as they slide along the rod, and raise them from contact with the gauges 51. After passing this curve the records move 45 down the inclined portion of the rod by gravity.

Group D, which embraces the reproducing mechanism, includes the turntable already referred to, and tone-arm devices for use 50 therewith, supported from one side of the

machine in the following manner:—Attached to the side of the frame 2 is a bracket 65, on which are bearings 66, in which is journaled a shaft 67, on one end of which is a head 68, in which is rotatably mounted 70 a turret 69, in which is pivoted a tone arm 70, so as to have a limited movement in a vertical plane. On the end of said tone-arm is a pick-up casing 71, provided with the usual needle for following the grooves of the record. On the other end of the shaft 67 is a bevel-gear wheel 72, in mesh with a similar wheel 73 on the end of a rock-shaft 74, journaled in the lower part of the frame. To the inner end of said shaft is fixed an arm 75, (Fig. 2) at the outer end of which is a roller 76, in engagement with the edge of a cam 77, fixed on the shaft 22. A spring 78 connects the arm 75 with the frame 2, and insures a positive engagement of the roller 76 with said cam. Projecting from the turret 69 is a pin 79, the insulated head of which is adapted to contact with one of the terminals of a switch 80. Stop-screws 81 and 82 are also provided to limit the movement 85 of the tone-arm in either direction.

As the tone-arm 70 reaches the end of its inward movement on the record the switch 80 is closed, closing the circuit to the motor 26, and starting the shaft 22. By the action 90 of the cam 77 the shaft 74 is then rocked, also rocking the shaft 67, and tipping the tone-arm upwardly at the side of the machine, out of the way of the record conveying devices. As it approaches the end of the 95 movement the tone-arm and pick-up thereon, tip back of their own weight into the position shown in broken lines in Fig. 3, and upon being again lowered over the record will be in position to again start the playing 100 of the record. After one record has been removed from the turn-table and another one positioned thereon the movement of the shaft 67 is reversed, carrying the tone-arm back to operating position, with the switch 80 again 105 open. The outer end of the tone arm is also provided with wires 83, for connection with a radio apparatus.

A switch 84 is attached to the frame 2 at one side of the machine, which switch is connected with the electric system of the machine, and the terminals of which are arranged to be normally closed. One of said terminals is in the line of movement of a roller 85 on the cam 77, so that at one point 115 in the rotation of said cam the switch will be opened and the movement of the motor 26 interrupted. This condition continues while the piece on the record is being reproduced, and upon the tone-arm 70 reaching the end 120 of its inward movement the switch 80, which is on an independent circuit to the motor, is closed by the pin 79, and the motor put in operation again. This results in the operation 125 of the shaft 22, and rocking of the arm 130

75, which movement is communicated to the tone-arm shaft 67, tipping the tone-arm and pick-up thereon upwardly and to one side of the machine, out of the way of the record receiving and handling frame. The continued rotation of the shaft 22 actuates the arm 54, operating the shaft 46, and carrying the record that has just been reproduced upwardly and positioning the same on the rod 61. The arms 49 are then moved downwardly into inclined position to receive a record from the pile, whereupon they again move downwardly, depositing the record on the turn-table, as before described. At this point the roller 85 opens the switch 84, and the motor 26 and shaft 22 are again motionless. The motor 41 has been in movement meanwhile, and as soon as the record is deposited thereon the tone-arm is lowered into position to start the reproduction of the piece. This return movement of the tone-arm necessarily precedes the shutting off of the motor 26, and the switch 80 is open at this time, so that the motor will not be put in operation thereby.

A switch 86 is also attached to the frame 2, and is wired for connection with the electric system extending to the motor 41. The longer arm of the switch 86 is formed at its end with a bend which is in the line of travel of a trip 87 fixed to the tube 8, and upon said tube reaching the end of its upward movement, with the last record on the disk 11 discharged, said switch will be opened by the trip 87, interrupting the movement of said motor. Upon more records being placed on the storage disk the trip is moved downwardly, and the switch permitted to close again.

In Fig. 4 is shown a diagrammatical detail of the electric system and its application to the various devices. Two main wires A and B lead to the motor 41, and by wires C and D to the motor 26. The wire D leads to the switch 80, which is connected with the motor 26 by a wire E. The switch 84 is also connected with the wires D and E. At F is indicated a switch for opening the circuit of the entire system, when desired, and the switch 86 is shown cut into the wire B.

It will be understood that the operation of the machine is continuous, after the storage devices have been supplied with a quantity of records, one record at a time being fed from the pile and delivered to the reproducing devices and later transferred to the re-assembling mechanism. In machines of this type which are now in use the limit of records that can be handled at a single loading is twelve, whereas the present machine can be adapted for operation with double that number, or most any number, within reason. Other changes and adaptations can

be made without departing from the scope of the invention.

What I claim, and desire to secure by Letters Patent, is;

1. In a record changing mechanism, a storage device comprising a fixed rod, a tubular member slidable thereon and provided with a record support at its upper end, means for impelling the tubular member in a given direction, means for holding said tubular member from movement, means for limiting the movement of records on said support, movable to permit the release of one thereof, and means for the momentary release of said means for holding said tubular member, to permit a predetermined movement thereof.

2. In a record changing device, a storage means for records, comprising a record supporting table, a tube connected therewith, a rod in said tube projected above said table and forming a central support for records stored thereon, means for constantly impelling said tube in a direction to discharge said records, a brake for said tube, capable of holding the same at any point in its movement, a retaining arm in line with said rod, means for moving the same out of line therewith to release the uppermost record, means for momentary release of said brake, and means for holding said retaining arm in line with said rod at such intervals of temporary release of the brake.

3. In a record changing mechanism, a storage device comprising a table held in inclined position, a tube connected with said table, and means for impelling said tube in a direction to discharge records held on said table, means for holding said tube from movement, means for momentarily releasing said last-named means, a rod extending through said tube and table, forming a retainer for records supported thereon, an arm swingingly mounted above said table, in line with said rod, and provided with means for engagement with the central opening of a record, means for swinging said arm to one side, means for holding said arm from movement during the momentary release of said tube-holding means, said means when properly positioned also permitting the arm to be swung to one side to permit loading of the storage device.

4. In record changing mechanism, a storage device, comprising a support held in an inclined position, a retaining rod for records centrally thereof, means for constant upward feed of said support, a stop in line with said support provided with a pin for engagement with the opening in a record, means for moving said stop to one side and giving initial movement to the uppermost record on said support, and means for arresting the feed of said support while said stop is in operation.

5. In a record changing mechanism, a storage device, capable of holding a plurality of

disk records in position for automatic discharge therefrom, mechanism for receiving records one at a time from said storage device and delivering the same to a reproducing mechanism, a reproducing mechanism, including a tone-arm and pick-up thereof, and means for moving said tone-arm upwardly and to one side of the machine, and to a point from which it will move by gravity to a position ready for another reproducing movement when it is returned to operating position.

In testimony whereof I affix my signature.
PAUL H. SCHULZ.
